SMALL GUN FOR PERFORATING CASING
IN OIL WELLS

Theodore A. Huber, Houston, Tex., assignor, by
mesne assignments, to Standard Oil Develop-
ment Company, Elizabeth, N. J., a corporation
of Delaware

Application September 11, 1950, Serial No. 184,161

2 Claims. (Cl. 164—0.5)

1

This invention relates to guns for perforating pipe in oil wells or the like and more particularly to guns which are small enough to run through tubing in a well for perforating casing beneath the tubing.

Guns and explosives have long been used for perforating casing in oil wells and the art is well developed. As commonly constructed the barrels of guns used for such purposes are fixed horizontally in a carriage and these barrels approach in length, as far as is practical, the diameter of the casing so as to obtain the maximum fire power. If shaped charges of explosives are used instead of guns which fire bullets, these also have been fixed in a carriage or gun body. Even under the best conditions, effective perforation of oil well casing, and the cement which usually surrounds it, is difficult to accomplish, and since the size of the gun or explosive is important, casing perforators used heretofore have not been run into the well through tubing or other pipe smaller in diameter than the casing.

It has recently been proposed to perform certain operations including the perforating of casing in an oil well while tubing is in it. See for example application of Theodore A. Huber Serial No. 133,025, filed December 15, 1949, for "Method of Completing and Repairing Oil Wells" where the use of a casing perforating gun capable of being run through tubing is required. Large savings in time and cost can be effected in this way if effective perforation can be accomplished.

Small guns are, of course, old in the art and even if they were not, no invention would be involved in merely changing the dimensions of known guns. But from experience it has been found that, in order to solve the problem of perforating casing beneath tubing in the well, more must be done than merely provide a small diameter gun and gun carriage, for small guns have barrels too short to provide adequate firing power unless they are placed in a position close to their targets when they are fired.

In accordance with the present invention, it is proposed to solve the problem of providing effective firing power to perforate casing with an assembly which is run into and out of the well through tubing by arranging the guns in their carriage on trunnions and by providing means for rotating them from the vertical positions which they occupy while being lowered into the well, into horizontal firing positions. Inasmuch as the guns may be fired by electricity, it is convenient to employ an electric motor to rotate them exactly the right amount. It is also con-

2

venient to employ limit switches to cause the firing to occur when the barrels are horizontal and to return the guns to vertical position so that they can be retrieved from the well if they are not destroyed upon firing.

The objects of the invention will be apparent from the following description, taken in connection with the accompanying drawings, in which:

Fig. 1 is a view in vertical cross-section of a portion of an oil well with a gun being lowered through tubing therein.

Fig. 2 is a similar view of a lower portion of the well of Fig. 1 with the gun thereof in firing position.

Fig. 3 is a similar view of the portion of the well of Fig. 2 showing how bullets are fired from the gun into the earth formations.

Fig. 4 is a similar view of the portion of the well of Fig. 3 showing the gun being retrieved through the casing.

Fig. 5 is a similar view of the lower portion of an oil well showing how shaped charge explosives may be employed to carry out the principles of the invention instead of a bullet gun.

Fig. 6 is a similar view showing how a gun using shaped charges may be retrieved through tubing in the well.

Fig. 7 is an enlarged fragmentary view, partly in cross-section of a gun somewhat similar to that illustrated in Figs. 1 to 4 and illustrating one system for rotating the gun barrels and for firing the guns when they are in the desired position.

Fig. 8 is a transverse cross-sectional view of the gun of Fig. 7 showing a detail of the driving mechanism for rotating the guns, the view being taken on the line 8—8 thereof.

Fig. 9 is a transverse cross-sectional view of the gun of Fig. 7 showing a detail of the limit switch employed, the view being taken on the line 9—9 thereof.

Fig. 10 is a transverse cross-sectional view of the gun of Fig. 7 showing a detail of the trunnions and driving mechanism, the view being taken on the line 10—10 thereof.

Fig. 11 is a circuit diagram of the gun of Fig. 7.

Referring to the drawings in detail and first to Figs. 1 to 4 which illustrate a sequence of operation of a gun constructed in accordance with the principles of the invention, it will be seen that the casing of an oil well is there shown at 12. A tubing 13 is positioned in the well with its lower end above the portion of the casing which is to be perforated, as shown in Figs. 2, 3, and 4.

Within the tubing 13, as shown in Fig. 1 and

beneath it, as shown in Figs. 2, 3, and 4, is a gun body or carriage 14 which is lowered into the well on a cable 15. This carriage may be made of steel and it is of cylindrical shape with a number of slots 16 provided transversely to accommodate gun barrels 17 which are mounted for rotation in the slots 16 by trunnions 18.

The gun barrels 17 are of a length greater than the diameter of the tubing 13 and only slightly less than the diameter of the casing 12. In order for them to be lowered into the well through the tubing, it is necessary that they be held in a vertical position as shown in Fig. 1. After the carriage has passed out of the bottom of the tubing, the barrels 17 may be rotated to the horizontal position as shown in Fig. 2. The carriage 14 can then be raised and lowered by the cable 15 and the guns fired individually at different depths, or all of the guns may be fired at the same time, or nearly so, in accordance with well known perforating technique.

If the guns are of the type which shoot bullets, each barrel 17 may be loaded at both ends with the explosive charge in the center, as taught in the patent to Mims No. 1,582,184, with the result that bullets 20 are fired into the casing 12 and surrounding earth formation 21 in both directions as shown in Fig. 3. With such an arrangement, there is little strain on the trunnions 18 for the reactive firing forces balance out. However, it is within the purview of the invention to load each barrel 17 with only one bullet so as to increase the effective gun barrel length and secure greater penetration, as described hereinafter and shown in Fig. 7.

After the bullets have been fired, the barrels 17 may be rotated back into the vertical position as shown in Fig. 4, so that they can be pulled back up through the tubing 13 to remove them from the well.

Mechanism including a reversing screw like the level-winder on a fishing reel may readily be provided by those skilled in the art for causing the barrels to reverse their direction of rotation after firing. Provision of such means for reversing direction enables the use of a stronger gun body or carriage, because the slots 16 therein may then be reinforced along one side at the top and one side at the bottom. However, in the arrangement described hereinafter and shown in Figs. 7 to 10, the barrels rotate a total of 180 degrees and do not reverse their direction of rotation. In any event the guns are fired after they are rotated 90 degrees, or approximately so.

If shaped charges of explosive are used to perforate the casing, or if the gun or explosive is otherwise designed to concentrate the force of the explosion upon points opposite the ends of the gun, as taught in the Mims Patent 1,582,184, it may be convenient to have the barrels blow up as shown in Fig. 5. Fragments of the barrels are there shown at 22 and holes in the casing and earth formation are shown at 23. The gun carriage 14 then comes back out of the well empty, as shown in Fig. 6.

Figs. 7 to 10 of the drawing show one way of rotating the barrels 17 on their trunnions 18. In Fig. 7, the barrels 17 are shown as bullet guns with one bullet 24 in each barrel. It will be observed that the mouth of upper barrel 17 shown in Fig. 7 is at the top while the mouth of the lower barrel 17 is at the bottom when the barrels are in their running-in (full line in Fig. 7) position. The barrels may be thus alternately positioned. Since all the barrels rotate counter-

clockwise, as viewed in Fig. 7, when they take their horizontal positions, as shown in dotted lines, the upper barrel 17 will fire to the left while the lower one will fire to the right. The same staggering of the perforations, that is, one to the right and one to the left could be obtained by loading all the barrels alike, say with their muzzles pointing upwardly, in the full line position of Fig. 7 and by causing alternate ones to rotate in opposite directions, that is, half clockwise and half counter-clockwise.

For rotating the barrels, one trunnion 18 of each barrel may be provided with a gear 25 driven by a worm 26 on a shaft 27 which extends downwardly through the carriage 14 from a chamber at the top. Alternate worms 26 may be right and left hand screws, if desired, to cause half of the barrels to rotate in opposite directions. Within the chamber is an electric motor 28, connected to the shaft 27 by suitable gears 29 and 30.

Also within the chamber in the top of the carriage 14 are two limit switches, the blades 31 and 32 of which are insulated and mounted on a rider 33 which is threaded upon a screw 34 connected to the shaft of the motor 28. The blade 31 engages a ground bar 35 over most of the path of travel of the rider 33. This blade is in the circuit for the motor and the length of the ground bar 35 is such, and the pitch of the screw 34 is such that the barrels 17 rotate 180 degrees from the position shown in full lines in Fig. 7 before the blade 31 leaves the lower end of the ground bar 35. When it does leave, the circuit of the motor 28 is broken and the rotation of the barrels 17 cease.

The blade 32 is designed to strike an insulated contact 36 at a time when the rider 33 has traveled half way from the position shown to the point where blade 31 leaves the ground bar 35. The contact 36 is connected to the firing fuses of the guns, so that they fire automatically when the barrels 17 have rotated 90 degrees from their vertical position.

Electric current is supplied to the motor 28 and the fuses of the guns through a conductor in the cable 15. The circuit may be like that shown in Fig. 11. As there shown, the conductor 37 of the cable has a switch 38 at the surface of the ground in series with the source of current 39. One pole of the source 39 is grounded as shown at 40 so that if one terminal of the motor 28 is grounded in the well bore, the motor is energized. This grounding occurs so long as blade 31 is engaging ground bar 35, which may be connected to the carriage 14 which is located in the mud or other fluid in the well bore or in contact with the casing of the well. Until the switch 38 is closed at the surface of the ground, no current can pass down the cable however so the barrels 17 are not rotated until the carriage is in the desired position in the well bore. The conductor 37 of the cable 15 is also connected to the blade 32. Hence when blade 32 engages contact 36, the fuses 41 of the guns are energized by the source 39, assuming the switch 38 remains closed.

While only a few embodiments of the invention have been shown and described herein, it is obvious that changes may be made without departing from the spirit of the invention or the scope of the annexed claims.

What I desire to claim is:

1. In an arrangement for perforating casing in oil wells or the like, an elongated carriage small enough in diameter to enable it to be run

into the well through tubing inside the casing to be perforated, a plurality of guns mounted individually for rotation in said carriage, each of said guns having a diameter less than the diameter of the tubing and a length greater than the diameter of the tubing but less than the diameter of the casing, and means for rotating said guns simultaneously from their vertical position longitudinal of the carriage into a position transverse thereof, each of said guns being loaded with only one bullet, alternate guns being positioned with their muzzles at opposite ends so that when the guns are rotated in the same direction of rotation to their horizontal positions, adjacent guns will be facing in opposite directions, thereby being in a position to perforate the casing with staggered holes when said guns are fired.

2. In an arrangement for perforating casing in oil wells or the like, an elongated carriage small enough in diameter to enable it to be run into the well through tubing inside the casing to be perforated, a plurality of guns mounted individually for rotation in said carriage, each of said guns having a diameter less than the diameter of the tubing and a length greater than the di-

ameter of the tubing but less than the diameter of the casing to be perforated, means for rotating said guns simultaneously from vertical positions longitudinal of the carriage through arcs of 180° to second vertical positions longitudinal of the carriage, and means for firing the guns at a time when they have traversed approximately one-half of their 180° arcs of travel, each of said guns being loaded with one bullet, alternate guns being positioned with their muzzles at opposite ends so that when the guns are rotated in the same direction of rotation over their arcs and fired, they will be facing in opposite directions, thereby perforating the casing with staggered holes.

THEODORE A. HUBER.
